UNITED STATES PATENT OFFICE.

HERBERT PERCY WARREN, OF AVOCAS VILLA, SOUTH AFRICA.

POST FOR SUPPORTING TENNIS NETS OR THE LIKE.

Application filed April 27, 1926. Serial No. 104,958.

This invention relates to posts for supporting tennis nets or the like which are suspended normally from a wire, cord or similar flexible member capable of being placed under tension and has for its object improved means, of the type in which the free end of the cord or the like is attached to a member such as a sleeve, the vertical position of which on one of the posts is adjustable at will, for enabling the tension of said member to be adjusted to enable the height of the net or the like to be varied.

In accordance with this invention one end of a wire, cord or the like to be strained passes in the known manner over a pulley at the top of a post and is hooked, or otherwise attached, to a sleeve slidable on said post, which sleeve is connected with, and adapted to be slidden along, the post in the direction to strain the wire or the like by means of, a lever pivoted to the post and a chain or other connecting member connected with said lever and said sleeve, whilst a second chain, adapted at one end to engage in one of a stepped series of notches formed in the sleeve and at the other end to engage with one of a stepped series of hooks attached to the post, is provided for securing said sleeve in the position to which it is moved, so as to retain the wire or the like under tension.

The invention is applicable to a variety of purposes of which the simplest is the tensioning of a clothes line, but primarily it is intended for use in connection with tennis nets, and the accompanying drawings illustrate one form thereof for the purpose last mentioned, Figure 1 being a sectional elevation of the post for one end of a net (not shown), Figure 2 an elevation of the post for the other end of the net, Figure 3 an elevation of the support or socket for a post as viewed from the right of Figure 1, whilst Figure 4 is an enlarged elevation of a detail as viewed from the left of Figure 2.

The posts *a* and *b* are of tubular metal and each is slotted longitudinally at its upper end as at *c* to give passage to a pulley *d* rotatable on a spindle *e* which passes through apertures in the post and in a sheet metal cap *f* which covers the upper end of the post. The post *a* has riveted thereto, in line with its pulley *d*, a longitudinal

series of hooks *g*, for the attachment of an eye *h* at one end of the cord *j* of the tennis net (not shown). The lower ends of the posts *a* and *b* are adapted to be received each in a tubular socket *k* to which are clamped plates *m* and *n*, disposed on opposite sides thereof and facing the direction of the strain to be imposed, i. e. the plates *m* and *n* lie in planes normal to the direction of the cord *j*. In order to facilitate true alignment of the pulleys *d* with one another when the posts *a* and *b* are placed in the sockets *k* (assuming the latter to have been embedded correctly in the ground) each socket *k* is slotted at its upper end as at *o* and a lug such as *p* adapted to be received in a slot *o* is secured to each post *a* and *b* by a clamp *q*.

The post *b* has slidable thereon a sleeve *r* furnished on one side with a hook *s* to which may be attached an eye *h* at the end of the cord *j*, and at the other side with a lug *t* to which are attached two lengths of chain *u* and *v*. Pivoted to the clamp *q* of the post *b* is a lever *w* with which the chain *u* is connected, said lever serving, when swung down, as indicated in broken lines in Figure 2, to slide the sleeve *r* down the post *b* and thus strain the cord *j*. Normally, when not required, the lever *w* is held close to the post *b* by a loop *x* pivoted to said post and adapted to be swung over the free end of said lever. The chain *v* is attached to the lug *t* of the sleeve *r* by the passage of one of its links through a slot *y* with stepped notches at the lower side thereof and others of its links may be engaged with any one of three hooks *z* riveted as an integral structure (see Figures 3 and 4) to the post *b*, the hooks *z* being stepped or arranged at different heights. The provision of the stepped notches in the slot *y* and the stepped hooks *z* enable a fine adjustment to be obtained when, after the sleeve *r* has been slidden on the post *b* by forcing down the lever *w*, it is desired to secure said sleeve and maintain the cord *j* under the required tension.

When the invention is used for purposes where it is required to vary the height of the poles *a* and *b* this may be done readily by altering the positions of the clamps *q*, *q*.

The leverage obtained by means of the improved arrangement enables the cord *j* to be

strained very readily in a much shorter time than would be occupied by the more usual ratchet and pawl mechanism.

I claim:—

- 5 Means for straining a wire, cord or like member comprising a post, a guide on said post over which said member passes, a sleeve slidable on said post, means on said sleeve adapted for the attachment thereto of said
10 member, a lever pivoted to said post and connected with said sleeve, said lever being

adapted to cause said sleeve to slide along said post, and a chain adapted at one end to engage with any one of a stepped series of notches on said sleeve and at the other ¹⁵ end to engage with any one of a stepped series of hooks attached to said post, said chain being adapted to secure said sleeve in the position to which it is moved, so as to retain the strained member under tension.

HERBERT PERCY WARREN.
